Primary Examiner — Sandra S Snapp*Assistant Examiner* — Leisha N Price(74) *Attorney, Agent, or Firm* — B. Craig Killough;
Barnwell Whaley Patterson & Helms(57) **CLAIM**

The ornamental design for an external pile guide for docks, as shown and described.

DESCRIPTION

FIG. 1 is a top perspective view of an external pile guide for docks showing the new design;

FIG. 2 is a bottom perspective view of the external pile guide for docks;

FIG. 3 is a top plan view of the external pile guide for docks;

FIG. 4 is a bottom plan view of the external pile guide for docks;

FIG. 5 is a front elevation of the external pile guide for docks;

FIG. 6 is a rear elevation of the external pile guide for docks; and,

FIG. 7 is a right side view of the external pile guide for docks in relation to FIG. 5; the left side of the external pile guide for docks is a mirror image of FIG. 7.

The broken lines showing of the L-shaped brackets illustrates the environment of the claimed design and forms no part thereof.

1 Claim, 5 Drawing Sheets(56)
